(57) **CLAIM**

The ornamental design for the safety cover for automotive brake pedal, as shown and described.

DESCRIPTION

FIG. 1 is a front perspective view of the safety cover for automotive brake pedal shown in a usage environment with an automotive brake pedal and additional surrounding environment drawn in broken lines.

FIG. 2 is a front perspective view of the safety cover for automotive brake pedal.

FIG. 3 is a bottom perspective view of the safety cover for automotive brake pedal.

FIG. 4 is a top plan view of the safety cover for automotive brake pedal.

FIG. 5 is a front elevation view of the safety cover for automotive brake pedal.

FIG. 6 is a bottom plan view of the safety cover for automotive brake pedal.

FIG. 7 is a rear elevation view of the safety cover for automotive brake pedal.

FIG. 8 is a right side elevation view of the safety cover for automotive brake pedal; and,

(Continued)

FIG. 9 is a left side elevation view of the safety cover for automotive brake pedal. The broken lines illustrate environment of the claimed design and form no part of the claimed design.
